UNITED STATES PATENT OFFICE.

ADRIAN ST. C. GARMAN, OF PHILADELPHIA, PENNSYLVANIA.

FOLDING AND EXTENSION TABLE.

1,223,782.

Specification of Letters Patent. Patented Apr. 24, 1917.

Application filed March 15, 1916. Serial No. 84,301.

To all whom it may concern:

Be it known that I, ADRIAN ST. C. GARMAN, a citizen of the United States, residing in the city and county of Philadelphia, State of Pennsylvania, have invented a new and useful Folding and Extension Table, of which the following is a specification.

My invention consists of a table which may render service as an ordinary table and 10 is convertible into an extension table and likewise into a folding table, means being employed for retaining the members thereof in comparatively fixed condition in either of the forms that it may assume, as will be 15 hereinafter set forth, and the novel features thereof pointed out in the claims.

The invention is satisfactorily illustrated in the accompanying drawing, but the important instrumentalities thereof may be 20 varied, as long as they are included in the scope of the claims.

Figure 1 represents a side elevation partly broken away of a table in normal condition embodying my invention.

Fig. 2 represents a side elevation of a portion thereof at a right angle to Fig. 1.

Fig. 3 represents a side elevation of the table in folded condition.

Fig. 4 represents a bottom plan view 30 partly in horizontal section of the table in the condition of an extension table.

Fig. 5 represents a section similar to Fig. 4, taken on the line 5—5 Fig. 1, the table, however, being in extended condition.

Fig. 6 represents a transverse section of a portion on the line 6—6 Fig. 4.

Fig. 7 represents a transverse section of a modification.

Similar numerals of reference indicate 40 corresponding parts in the figures.

Referring to the drawings.

1 designates the top of the table, the same being formed of sections 2—2 which may be separated and have an extra leaf or leaves 45 placed between the same after the manner of an extension table, as shown in Fig. 4, the closed condition of said sections being shown in Fig. 1.

The legs 3 of one section are connected 50 by the cross bar 4, and the latter is secured to said section by the hinges 5, thus permitting said legs to be folded comparatively parallel, as in Fig. 3.

The legs 6 of the other section are connected 55 by the cross bar 7, and the latter is attached to said section by the hinges 8, one

leaf of each of which is secured to said cross bar, on the other leaf of each of which is a portion of a sliding plate 9 being an extension of said leaf, the plates freely occupying 60 the keepers 10, on the under side of said last named section, thus permitting said legs 6 to be folded comparatively parallel, as also in Fig. 3, and as said section moves in the extension and closing of the table, the sliding 65 plates or leaves 9 play in the keepers 10, and likewise preserve the connection of said legs 6 with the adjacent section 2, by the relative hinges.

Connected with the opposite sections 2 on 70 the underside thereof are the slides 11 which are formed of members 12, 13 fitted to each other telescopically, see Fig. 4, whereby said sections are braced in both extended and closed positions, and when in the extended 75 position serves to support the extra leaf or leaves placed thereon, one of said slides being tubular forming a strong support for the other slide.

To the sides of the legs at or about the 80 top and foot portions thereof are pivoted the sectional braces 14 which are slotted in the direction of their lengths to receive the screws 15, whereby while each brace may be separated, and so lengthened with the motions of the table top in its extension, and returned to normal length in the closing of the top, said screws may be tightened by thumb nuts 16 thereon, and so prevent motions of 85 the braces in either direction. 90

As the braces are pivotally connected with the legs, the former may be folded with the latter, as shown in Fig. 3. In this case the pivots on the legs consist of the pins 17 and the screws 18, each of which is connected 95 with the adjacent leg and passes through the adjacent section of the brace and being provided with the nut 19, which when tightened renders the joint of the section with the leg immovable, and in this case, prevents the 100 folding of the legs when so desired.

To prevent the turning of the cross bar 7 by the hinges 8 on its section of the top, when so desired, said section has pivoted to it on its under side, the latch 20, which is 105 adapted to enter the recess 21 in the end of said cross bar as a keeper, see Fig. 4.

When the sections of the top are in closed position, they are connected and so prevented from separation by the latch 22, and pins 110 23, on the opposite sections respectively, the operations of which are evident.

While the table may render service as an ordinary table, the sections 2 being closed as in Figs. 1 and 2, and its members are held immovably together as one by the various screws and nuts employed for that purpose, it may also render service as an extension table, as in Figs. 4 and 5, its members then being held immovably together as one by the various screws and nuts employed for that purpose. Again, by loosening said nuts and screws the legs and the side braces may be folded one on the other, and the top 1 placed in vertical position, as in Fig. 3, when the table is in comparatively flat condition, the nuts and screws then being tightened, when the table may be stowed-away in small space, or is in condition for convenience of handling, packing, and transportation.

In the turning motions of the cross bar 7 to which the legs 6 are attached, as said legs are folded as in Fig. 3, or in unfolding said legs and placing them in upright position in the normal condition of the table as in Fig. 1, said cross bar, the extended leaves or plates 9 of the hinges 8 slide in the keepers 10, thereby permitting sliding motions of said cross bar 7 on the movable section 2 of the table top, while, however, preserving the hinged connection of said cross bar with said section 2, as has been stated.

The slotted braces 14 are strengthened by means of tongues 24 formed on the inner sides of members thereof, the same freely entering the grooves 25 in the opposite members, see Fig. 7, and adapted to play in said slots, while the braces are at rest and moved in opposite directions during the extension, the closing, the folding, and the unfolding of the table, thus strengthening said braces.

When the parts are in folded condition, they are held thereat by the hook 26 and pin 27, which are suitably applied, and plainly shown in Figs. 2, 3, and 4.

Copies of this patent may be obtained for five cents each, by addressing the "Commissioner of Patents, Washington, D. C."

Having thus described my invention what I claim as new and desire to secure by Letters Patent, is:

1. A table provided with legs and having its top formed in sections, cross bars hinged to the opposite sections, slides formed of telescopic members connected with the opposite cross bars, and braces formed of sectional members connecting the legs of the opposite sections, and means for tightly connecting the latter-named members. 55

2. A table provided with legs and having its top formed in sections, a cross bar hinged to one section and connecting the legs of said section, a cross bar hinged to the other section and connecting its legs, means connecting the opposite top sections whereby the table is convertible into an extension table, means permitting the legs of both sections to fold substantially parallel with each other and with the top, and braces pivotally connecting the legs of the opposite sections of the table, said braces being formed of extensible slotted sections, and means for tightly connecting the latter. 60

3. A table provided with legs and having its top formed in sections, a cross bar hinged to one section and connecting the legs of said section, a cross bar hinged to the other section and connecting its legs, means connecting the opposite top sections whereby the table is convertible into an extension table, means permitting the legs of both sections to fold substantially parallel with each other and with the top, and slotted sectional braces pivotally connected with the legs of opposite sections and foldable substantially parallel with the legs and top, said braces forming means for tightly connecting the legs. 75 80

ADRIAN ST. C. GARMAN.
